REFRIGERATION SYSTEM INCLUDING A
LOAD CONTROL APPARATUS

Edward L. Schulz, Lakewood, Ohio, and Edward A. Bailey, Marietta, N. Y., assignors to Carrier Corporation, Syracuse, N. Y., a corporation of Delaware

Application February 2, 1946, Serial No. 645,185

3 Claims. (CL. 62—2)

1

This invention relates to the art of refrigeration and more particularly to a control arrangement for regulating the production of refrigeration effect, the control arrangement being responsive to variations in load conditions to compensate for conditions of overload arising from unforeseen causes.

In air conditioning systems such as those used to condition buses, railway cars, etc., in which the compressor of the refrigeration system is driven directly from the engine of the bus, or a wheel of the car, it is desirable to provide some control means to prevent inefficient and ineffective operation of the system under conditions of overload. In some systems heretofore used, a high pressure cut-out has been provided for such purpose, the cut-out serving to discontinue operation of the compressor until the undesirable conditions have been remedied. It will be appreciated, however, in systems where the compressor is driven directly, such cut-outs cannot be used.

The chief object of the present invention is to provide a simple and ready control means for preventing the passage of refrigerant to the evaporator of a refrigeration system whenever load conditions result in undesirably high condenser pressure.

An object of the present invention is to provide a simple control means for refrigeration systems used in transportation vehicles for air conditioning which operates automatically upon the failure of condenser cooling to prevent damage to the refrigeration system.

A further object is to provide a refrigeration system embodying control means responsive to an increase in condenser pressure above a predetermined maximum which functions to prevent passage of refrigerant to the evaporator in cases where the system is unable to function effectively, and in which the system may be damaged or become inoperative by the failure of certain elements thereof.

A still further object is to provide a refrigeration system including a solenoid type valve in the discharge line disposed between the receiver and the expansion valve, the valve under normal conditions remaining in open position and permitting free passage of refrigerant to the expansion valve and evaporator while being actuated in response to excessive condensing pressure to move toward a closed position thus preventing the passage of refrigerant to the expansion valve.

A still further object is to provide a simple control for use in refrigeration systems in which the compressor of the system is continuously op-

erated and in which it is desired to prevent the passage of refrigerant to the evaporator under conditions of inefficient or ineffective operation.

A still further object is to provide a refrigeration system for use in transportation vehicles for air conditioning in which the compressor of the system is continuously operated and simple, efficient control means are provided to prevent the passage of refrigerant to the evaporator of the system under conditions in which the system is unable to function effectively.

This invention relates to a refrigeration system including in combination a compressor, a condenser, an expansion valve and an evaporator disposed in a closed circuit. A solenoid valve is disposed in the circuit between the condenser and the expansion valve and preferably between the receiver and the expansion valve. The solenoid valve is operable in response to a circuit breaker which is actuated by an increase in condenser pressure above a predetermined maximum. An increase in condenser pressure above a predetermined maximum actuates the solenoid valve to move it toward a closed position thus discontinuing the flow of refrigerant to the expansion valve and the evaporator.

The attached drawing illustrates diagrammatically a preferred embodiment of the invention.

Referring to the drawing, there is shown a compressor 2 preferably of the reciprocating type although it may be of any desired type connected to a condenser 3 by a line 4. Refrigerant from condenser 3 flows through line 5 to receiver 6. Discharge line 7 connects receiver 6 with an evaporator 8. An expansion valve 9 of the usual type well known in the art is disposed in discharge line 7. Evaporator 8 is connected to compressor 2 by suction line 10. Condenser 3 may be air or water cooled as desired; as illustrated it may be air cooled by means of a suitable fan.

Expansion valve 9 is actuated in the usual manner by means of a bulb 11 disposed adjacent the discharge end of evaporator 8. An equalizing line 12 extends between valve 9 and suction line 10 and serves to provide a pressure under the diaphragm of expansion valve 9 equal to the pressure at the discharge end of evaporator 8.

A control valve 13 is disposed in line 7 at a point preferably between receiver 6 and expansion valve 9. Control valve 13 may be a solenoid valve operable by means of coil 14. A circuit breaker designated generally at 15 is provided. A diaphragm 16 forming a portion of member 15 is connected to discharge line 7 through line 17 and is responsive to condenser pressure in line

7. A switch 18 is provided adapted to be moved to open and closed positions. Leads 18' and 19 are provided, lead 18' extending from a source of supply to switch point 20, while lead 19 extends from the source of supply to coil 14. A second switch point 21 is connected to coil 14 by line 22. An increase in condenser pressure above a predetermined level flexes diaphragm 16, moving switch 18 out of contact with switch point 21 opening the circuit and permitting valve 13 to close to prevent passage of refrigerant to expansion valve 9.

When condenser pressure again decreases to the predetermined level diaphragm 16 closes the circuit by engaging switch 18 with switch point 21 opening valve 13 to permit free passage of refrigerant to expansion valve 9.

In the normal operation of the refrigeration system of my invention free passage of refrigerant is permitted to expansion valve 9 and evaporator 8 in accordance with the load imposed upon the system. Assuming pressure in discharge line 7 (condensing pressure) exceeds a predetermined maximum of say 200 pounds, such pressure is exerted through line 17 against diaphragm 16. Flexing of diaphragm 16 actuates circuit breaker 15 and serves automatically to close solenoid valve 13. If the fault in the system is due to impaired condensing action, such as a break-down of the condenser fan or a failure of water if the condenser be water cooled, the increase in condenser pressure above a predetermined maximum prevents the passage of refrigerant to the evaporator and obviates damage to the system which might result. The control is automatic and consequently upon a decrease in condenser pressure the valve is actuated to open discharge line 7 permitting free passage of refrigerant to expansion valve 9.

In our co-pending applications, Serial Nos. 645,183, 645,184 and 645,186, filed February 2, 1946, February 2, 1946, and February 2, 1946, respectively, we have disclosed certain control means for modulating the action of the expansion valve in response to excessive loads imposed upon the system or in response to partial load conditions. It will be appreciated the present invention may be used in conjunction with the control arrangements disclosed in our co-pending applications if desired, or the present invention may be used alone in a refrigeration system to obviate harmful effects to the system which might result from operation under conditions of overload.

The present invention provides a simple and inexpensive means of control to prevent damage to a refrigeration system. The control means so provided is particularly desirable for use in refrigeration systems designed to be used in air conditioning applications such as transportation vehicles and the like. The control arrangement is responsive to condenser pressure above a predetermined level and operates automatically to prevent passage of refrigerant to the evaporator under conditions which might result in damage to the refrigeration system. The control arrangement is readily installed in existing systems and is of particular advantage when used in connection with refrigeration systems for buses.

While we have described and illustrated a preferred embodiment of our invention, it will be

understood our invention is not limited thereto since it may be otherwise embodied within the scope of the following claims.

We claim:

- 5 1. In a refrigeration system, the combination of a compressor, a condenser connected to the compressor, an expansion valve, a discharge line connecting the expansion valve and the condenser, an evaporator connected to the expansion valve, a suction line connecting the evaporator and the compressor, means disposed adjacent the suction line for governing operation of the expansion valve, a solenoid valve disposed in the discharge line adapted to prevent passage of refrigerant to the expansion valve, and means to operate the solenoid valve in response to an increase in condenser pressure above a predetermined level.
- 10 2. In a refrigeration system, the combination of a compressor, a condenser connected to the compressor, an expansion valve, a discharge line connecting the expansion valve and the condenser, an evaporator connected to the expansion valve, a suction line connecting the evaporator and the compressor, means disposed adjacent the suction line for governing operation of the expansion valve, a solenoid valve disposed in the discharge line, means for actuating the solenoid valve, said means being responsive to an increase in condenser pressure above a predetermined level, an increase in condenser pressure above a predetermined level actuating said means to move the solenoid valve to a closed position preventing passage of refrigerant to the expansion valve.
- 15 3. In a refrigeration system, the combination of a compressor, a condenser connected to the compressor, an expansion valve, a discharge line connecting the expansion valve and the condenser, an evaporator connected to the expansion valve, a suction line connecting the evaporator and the compressor, a solenoid valve disposed in the discharge line, and means for actuating the solenoid valve, said means including a circuit closing member, a diaphragm member to move said member to open and to close the circuit, and a line connecting the diaphragm member with the discharge line, the juncture of said line with the discharge line being disposed between the expansion valve and the condenser, an increase in pressure in the discharge line above a predetermined level actuating said diaphragm member to operate the circuit closing member thus tending to move the solenoid valve toward a closed position to prevent passage of refrigerant to the expansion valve.
